UNITED STATES PATENT OFFICE.

JAMES A. HORTON, OF PROVIDENCE, RHODE ISLAND, ASSIGNOR TO IROQUOIS MACHINE COMPANY, OF NEW YORK, N. Y., A CORPORATION OF NEW YORK.

DIE-HAMMERING MACHINE.

No. 802,691.

Specification of Letters Patent.

Patented Oct. 24, 1905.

Application filed May 21, 1903. Serial No. 158,083.

To all whom it may concern:

Be it known that I, JAMES A. HORTON, of Providence, in the county of Providence and State of Rhode Island, have invented certain new and useful Improvements in Die-Hammering Machines, of which the following is a specification.

This invention relates to means for hammering metallic articles, such as wire-drawing dies, to condense and compact the metal at a certain part or parts, the part compacted in a wire-drawing die being that which contains the mouth or smaller end of the wire-reducing orifice of the die.

A wire-drawing die as ordinarily made is a block of steel having a tapering orifice extending through it, the smaller end of the orifice corresponding to the gage of the wire leaving the die while being reduced by its passage through the die. The wear of the die causes a gradual enlargement of the reduced end of the orifice. To compensate for this enlargement, it is customary to hammer the die on the side containing the reduced end of the orifice, the hammering operation compacting and condensing the metal and thus reducing the size of the smaller end of the die. This hammering operation usually closes the smaller end of the die or interferes with its symmetry; but this is compensated for by reaming out the closed part of the orifice with a suitable tool.

My invention has for its object to enable the operation above described to be performed more rapidly, accurately, and to better advantage than heretofore; and to this end it consists in the improvements hereinafter described and claimed relating to a wire-die-hammering machine.

Of the accompanying drawings, forming a part of this specification, Figure 1 represents a top plan view of a wire-die-hammering machine embodying my invention. Fig. 2 represents a side elevation of the same, the die being shown in section in position to be operated on by the machine. Fig. 3 represents an end elevation. Fig. 4 represents a section on line 4-4 of Fig. 1.

The same reference characters indicate the same parts in all the figures.

In the drawings, *a* represents the bed or base portion of the machine, the same being provided with a raised anvil *b* to support the die *c*, which is to be hammered.

d represents a shaft journaled in bearings 55 on the base *a*, said shaft being rotated by power suitably applied—for instance, as by a belt running on a pulley *d'*, affixed to said shaft. The shaft is provided with a cam *e*, which imparts motion in one direction to the hammer 60 hereinafter described, said hammer being reciprocated in a path which causes it to move toward and from the anvil *b*.

The hammer above mentioned is composed of a head *f*, preferably tapered to form a reduced striking end or peen *f'* and a resilient helve *f''*, attached at one end to the head *f* and at the other end to a block or rocker *f'''*, which is mounted to oscillate on centers or pivots *f''''*, affixed to ears on the supporting-frame. The block or hub-block *f'''* and the helve in the vicinity of the pivotal axis of the hammer may be termed the "hub" portion of the hammer.

g represents a spring which is attached at 75 one end to a lever *o* or other suitable support and at the other end to a lug *g'*, affixed to the helve *f''*. Said spring tends to pull the helve and the hammer-head downwardly.

The cam *e* is arranged to act on a nose or 80 projection *f''''* on the rocker *f'''*, the arrangement being such that the rotation of the cam in the direction indicated by the arrow in Fig. 2 tends to raise the helve *f''* and the hammer-head *f*. It will be seen, therefore, that when 85 the shaft *d* is rapidly rotated the cam *e* and spring *g* coöperate in rapidly vibrating the helve *f''* and reciprocating the head *f* toward and from the anvil *b*.

h represents a fixed fulcrum-piece supported by the frame *a* at a point between the oscillating block *f'''*, supporting the resilient helve, and the hammer-head *f*. Said fulcrum-piece is arranged to arrest the downward movement of the helve with the hammer-head raised 95 above the die *c*, which rests upon the anvil, as shown in Fig. 2, so that if the helve *f''* were rigid the hammer could not strike the die. The arrangement of the fulcrum *h* is such, however, that the resilience of the helve enables the hammer to reach and strike the die in consequence of the flexure of the helve after it comes in contact with the fulcrum *h*. The hammer is thus caused to strike a whipping blow at each downward movement of the helve, the fulcrum preventing the rebound of the hammer from causing another blow on the die, so that each downward movement of the

helve causes one and only one blow of the hammer upon the die. The blows of the hammer are thus made uniform in force and the condensing and compacting action of the hammer is made more effective than would be the case if the fulcrum h were not employed.

- j represents a vertical pin located in a cavity formed for its reception in the anvil b , the upper end of said pin being tapered and formed 10 to enter the tapered orifice c' in the die c . The said pin or projection therefore engages the die and prevents it from slipping about edge-wise on the anvil, and is also a device for side-shifting and centering the die. In case the 15 die is placed carelessly on the anvil, with its orifice not quite in proper position, the pin j , engaging the inclined side of the orifice and being forced upwardly by the spring k , presses on the nearest wall of the orifice and shifts the 20 die sidewise until the orifice is exactly central over the pin. At the same time the pin permits the die to be rotated upon the anvil so as to bring different parts of its surface into the path of the hammer. The pin j is preferably 25 yieldingly supported by means of a spring k , so that the pin may conform to the taper of the orifice c' in the die. Said pin is somewhat eccentric to or out of alinement with the path of the hammer, so that the center of rotation 30 of the die, which is turned or rotated by the operator's hand, causes the hammer to condense and compact a circular area on the surface of the die, the diameter of said area depending upon the degree of eccentricity of 35 the pin j . It will be observed that the point of the hammer-head f strikes on the side of the die-opening c' away from the fulcrum of the hammer—that is, the centering-pin j is located between the striking-point of the hammer and the fulcrum h thereof. This arrangement 40 has the effect of giving the hammer a slight drawing or hooking blow toward the die-opening, which is more effective than a straight-line blow in reducing the diameter 45 of the opening.

- I prefer to provide means for varying the relative positions of the pin j and the path of the hammer f , or, in other words, the eccentricity of the pin, to the end that the area 50 which is hammered may be correspondingly varied. This result is accomplished, as herein shown, by providing the helve f^2 with longitudinal slots f^6 , through which pass the attaching-screws f^7 , which secure the helve to 55 the rocker f^3 . By loosening the screws f^7 and adjusting the helve lengthwise the distance between the path of the hammer and longitudinal center of the pin j may be increased or diminished.
- 60 m represents a presser-foot adapted to yieldingly hold the die against the anvil b . Said presser-foot is preferably a curved resilient metal arm attached at one end to the supporting-frame by the pivot m' and having its other 65 end curved downwardly and formed to bear

upon the upper side of the die without preventing the rotation of the die upon the pin j . The presser-foot is provided with an opening into which the hammer descends in striking the die. It is evident that this presser and 70 the anvil constitute a loose-holding clamp which permits the die to be rotated by the operator's fingers about the pin j as a center. The presser m is normally elevated through a link connection m^2 and a lever o , pivoted at 75 o' to the frame, said lever being raised by a spring q and depressed by a treadle connection r . To the other arm of the lever is attached a link p , connected with the heel of the hammer-helve f^2 , so that when the treadle 80 which is attached to the connection r is released by the operator the hammer f and presser m will be elevated, the spring q being of greater effect than the spring g .

The fulcrum h is preferably adjustable vertically to vary the force of the hammer-blow. This vertical adjustment may be provided for by giving the fulcrum-piece an inclined lower edge h' , the same resting on the inclined bottom of a slot in a post a' on the supporting-frame, the inclined surfaces constituting wedging-members. The attaching-screw a' , which secures the fulcrum-piece, passes through an inclined slot h^2 in the fulcrum-piece.

Among the advantages of my invention 95 may be mentioned the following in addition to some already indicated.

First. The striking blow of the hammer is effected by a spring instead of wholly by the weight of the hammer, as is frequently the 100 case. This enables the hammer to strike a quick sharp blow, lightens the parts, and enables the hammer to be put out of action at any desired instant.

Second. The hammer is rendered inoperative 105 by means which act directly on the hammer.

Third. The parts are normally in position for insertion of the work—that is, the hammer and presser are both raised, so that the work 110 may be positioned on the anvil without first operating or preadjusting the mechanism.

I claim—

1. A die-hammering machine comprising an anvil, a hammer coöperating therewith, die-controlling means, a presser, yielding means normally elevating said presser and mechanism connected to said presser and said hammer for simultaneously depressing said presser upon a die supported on the anvil, and bringing said hammer into operation.

2. A die-hammering machine comprising an anvil, a pivotal hammer having a head and resiliently constructed between its pivot and the head, a non-yielding abutment which rigidly arrests the hammer at a point in the resiliently-acting portion, and hammer-retracting means constructed to abruptly release the hammer.

3. A die-hammering machine comprising 130

die-supporting means, a pivotal hammer having a resilient helve and a striking-head thereon, an abutment arranged to engage and arrest said helve between the pivot and head

5 of the hammer, means for positively retracting the hammer, and means for yieldingly projecting it into coöperation with said abutment whereby a whipping blow is delivered.

4. A die-hammering machine comprising a 10 resilient pivotal hammer, means for retracting and abruptly releasing the same, an abutment to arrest a portion of said hammer short of striking position, leaving the rest of the hammer free to complete its stroke, and relatively 15 slidable wedge-formed surfaces for adjusting the operative position of said abutment.

5. A die-hammering machine comprising an anvil, die-centering means, a pivotal resilient 20 hammer, and hammer-operating means, said

die-centering means being located between the striking-point and pivot of the hammer, whereby a hooking blow toward the die-orifice is delivered.

6: A die-hammering machine comprising 25 die-supporting means, a pivotal hammer, a spring for projecting the same into striking position, means for positively retracting the hammer, a pivotal lever one arm of which is connected with the heel of the hammer, a 30 hammer-raising spring connected with the other arm, and a treadle connection attached to said lever.

In testimony whereof I have affixed my signature in presence of two witnesses.

JAMES A. HORTON.
